UNITED STATES PATENT OFFICE.

FRANCIS W. H. CLAY, OF EDGEWOOD PARK, PENNSYLVANIA, ASSIGNOR TO JO. BAILY
BROWN, OF PITTSBURGH, PENNSYLVANIA.

BOTTLE-CLOSURE.

1,191,567.

Specification of Letters Patent. Patented July 18, 1916.

Application filed August 27, 1914. Serial No. 858,816.

To all whom it may concern:

Be it known that I, FRANCIS W. H. CLAY, a citizen of the United States, residing at Edgewood Park, in the State of Pennsylvania, have invented certain new and useful Improvements in Bottle-Closures, of which the following is a specification.

My invention relates to metallic caps for bottles and jars, etc., and particularly to means for locking and unlocking the closure.

The invention is illustrated in one form as applied to a milk bottle in the accompanying drawing, wherein—

Figure 1 is a central vertical section of a jar with a cap in place thereon. Figs. 2 and 3 are side elevations at right angles to each other of a cap provided with an opening device, Fig. 4 being a plan view of the same. Fig. 5, shows an alternative form in which the locking flange is locked against opening. Fig. 6 illustrates the mode of cutting the blank for this latter device, and Fig. 7 is a side elevation of the locking lugs in place.

In several patents heretofore granted to me I have shown a bottle cap which engages the glass by the edges of a slotted metal flange, so as not to depend upon friction for the hold on the bottle, such caps also having the feature of maintaining a pressure by the strain of the metal itself rather than by the elasticity of the packing employed. As shown herein, I may provide a cap 8 with a paper packing 9 resting on the mouth of the bottle 10, the sides of the cap 11 being in loose circumferential contact with the bottle flange and the slotted and indented parts of the flange 12 directly engaging the glass by the edge of the metal. Properly proportioned the inwardly bowed portions 12 must be sprung outward in order to go over the bottle flange as pressure is applied, and when such pressure is removed the arches 12 have a direct hold on the glass and are placed under a downward stress. As long as the parts are in position as shown in Fig. 1, it is evident that any pressure under the cap, pushing the arches 12 upward, also tends to force them inward and therefore locks the cap tighter. Meanwhile the seal is kept by the resiliency of the metal in the arches 12. If the generally conical shaped skirt formed by the series of inward arches 12 and the intervening connecting arches 13 be in anywise expanded circumferentially,

the hold of the arches 12 may be loosened, and only by such separating of this conical skirt can the cap be removed. My present improvement contemplates any means for expanding the conical skirt. For instance, 60 I may provide the two lugs 14 and 15 turned up out of the metal of the skirt as shown in Figs. 2, 3 and 4, so that by pushing one in one direction and one in the other, the skirt can be spread and the cap removed. This 65 is easily done with the thumb and finger or any convenient tool for applying twisting movement to the lugs. In this form of the cap, the application to the bottle is made by simple downward pressure, snapping the 70 cap over the bottle flange and to better its hold on the bottle, I may provide the rib 16 shown in Fig. 2, or other stiffening means. Generally, there should be only enough metal on the outward arches 13, to safely 75 hold the flanged skirt and stand the pressure necessary where the cap is applied by a ring engaging the arches 13 as in my previous Patent No. 860,964, July 23, 1907. The present cap however, is easily applied by 80 hand pressure and can be used over again indefinitely, the metal not being permanently distorted.

In some instances it is desirable to absolutely lock the cap on the bottle, and in such 85 case the opening lugs may be made as shown in Figs. 5 to 7. The punched out portions 17, 18, are turned up at right angles so that the lug 19 engages the side of the lug 18, thus preventing a mere pressure on 90 the sides of parts 17, 18, from releasing the cap. The release is accomplished by a slight vertical displacement of the lugs 18 and 17 either with the fingers or by inserting a sharp tool in the small slot (20). As shown 95 in Fig. 7 a bit of sealing wax may be applied at X so that the bottle cannot be opened without breaking the seal. It will be seen that this provides ready means for sealing certified milk, etc. The same end 100 can be accomplished with the form of lug shown in Fig. 2 as by sealing the lugs 14, 15, together. The cap may be attached to the bottle by a wire through any opening therein and around the bottle as through 105 the lug 15.

The advantage of a bottle or jar cap which may be repeatedly applied by merely springing it into place, which is automatically locked on the bottle, not removed by any 110

ordinary blows and not disturbed by inside pressure in the bottle; which keeps its seal by the resiliency of the metal itself rather than by the packing, which may be removed by hand, and which may be at the same time sealed without interfering with the hand opening feature, all flow from the peculiar construction shown and the many advantages of the device will be apparent to those familiar with the art.

Having thus described my invention and illustrated its use, what I claim is the following:

1. A bottle sealing cap having a generally conical shaped flange with horizontally slotted portions engaging by their edges the flange of the bottle, and means for spreading the said conical shaped flange to release the hold on the bottle.
2. The combination with a flanged bottle mouth of a metallic sealing cap comprising a cover, a circumferential flange of general conical form slotted at intervals and the slotted portions bowed inwardly to engage the bottle flange on the edge of the metal,

of a pair of lugs arranged on the conical skirt and adapted to circumferentially spread the skirt, substantially as described.

3. A bottle sealing cap comprising a cover and a dependent flange having circumferentially slotted arched portions engaging the bottle by the edges of the arch, and manually operated means for enlarging the flange to release said arches.

4. A bottle sealing cap having horizontally slotted arches adapted to be sprung into position on the bottle and engaging the bottle by the edges of the metal and means for loosening the grip of such arches comprising projections on the skirt of the cap adapted to be moved by hand, substantially as described.

In testimony whereof I have hereunto signed my name in the presence of the two subscribed witnesses.

FRANCIS W. H. CLAY.
